US00D937613S

(12) **United States Design Patent** (10) Patent No.: **US D937,613 S**
Brugger et al. (45) Date of Patent: ** Dec. 7, 2021

(54) **RETAIL DISPLAY**

(71) Applicant: **Apple Inc.**, Cupertino, CA (US)

(72) Inventors: **Alice Marlin Brugger**, San Francisco, CA (US); **Richard Coward**, San Francisco, CA (US); **Joshua Robert Edwards**, Santa Cruz, CA (US); **Tracey Adam Finger**, Miami Beach, FL (US); **Jean-Marc Gady**, Los Altos, CA (US); **Gabriel Lamb**, Burlingame, CA (US); **Gregory Guillaume Lepinard**, San Jose, CA (US); **Adam John Oestreicher**, San Francisco, CA (US); **Constantino Siampos**, Alameda, CA (US); **Moritz Wilsberg**, Rheinbreitbach, DE (US); **Stephen Yustiono**, Sunnyvale, CA (US); **Mi Zou**, San Francisco, CA (US)

(73) Assignee: **Apple Inc.**, Cupertino, CA (US)

(**) Term: **15 Years**

(21) Appl. No.: **29/774,967**

(22) Filed: **Mar. 19, 2021**

Related U.S. Application Data

(63) Continuation of application No. 29/738,978, filed on Jun. 22, 2020, now Pat. No. Des. 913,731, which is a continuation of application No. 29/719,595, filed on Jan. 6, 2020, now Pat. No. Des. 887,750, which is a continuation of application No. 29/694,970, filed on Jun. 14, 2019, now Pat. No. Des. 872,508, which is a continuation of application No. 29/650,766, filed on Jun. 8, 2018, now Pat. No. Des. 851,428, which is a continuation of application No. 29/599,805, filed on Apr. 6, 2017, now Pat. No. Des. 820,619.

(57) **CLAIM**

The ornamental design for a retail display, as shown and described.

DESCRIPTION

FIG. 1 is a top front perspective view of a retail display showing the claimed design;

FIG. 2 is a bottom front perspective view thereof;

FIG. 3 is a front view thereof;

FIG. 4 is a top front perspective view of another retail display showing the claimed design;

FIG. 5 is a bottom perspective view thereof; and,

FIG. 6 is a front view thereof.

The broken lines in the figures show portions of the retail display or environment that form no part of the claimed design.

1 Claim, 6 Drawing Sheets

UNITED STATES PATENT AND TRADEMARK OFFICE
CERTIFICATE OF CORRECTION

PATENT NO. : D937,613 S
APPLICATION NO. : 29/774967
DATED : December 7, 2021
INVENTOR(S) : Brugger et al.

Page 1 of 1

It is certified that error appears in the above-identified patent and that said Letters Patent is hereby corrected as shown below:

On the Title Page

In the Description, replace:

“The broken lines in the figures show portions of the retail display or environment that form no part of the claimed design.”

With:

--The broken lines in the figures show portions of the retail display that form no part of the claimed design.--

Signed and Sealed this
Twelfth Day of July, 2022

Katherine Kelly Vidal
